UNITED STATES PATENT OFFICE.

FRANK W. WATSON, OF CEDAR FALLS, IOWA.

SCAFFOLD.

1,222,053.

Specification of Letters Patent. Patented Apr. 10, 1917.

Application filed July 1, 1916. Serial No. 107,086.

To all whom it may concern:

Be it known that I, FRANK W. WATSON, a citizen of the United States, residing at Cedar Falls, in the county of Blackhawk and 5 State of Iowa, have invented certain new and useful Improvements in Scaffolds, of which the following is a specification, reference being had to the accompanying drawings.

10 This invention relates to certain improvements in scaffolds and has relation more particularly to a device of this general character especially designed and adapted for use in connection with roofs; and it is an object 15 of the invention to provide a scaffold of this general character having novel and improved means whereby it may be readily and effectively adjusted in accordance with the differing inclination of roofs and whereby the 20 same may also be adjusted in such a manner as to serve as a horse.

The invention consists in the details of construction and in the combination and arrangement of the several parts of my 25 improved scaffold whereby certain important advantages are attained and the device is rendered simpler, less expensive and otherwise more convenient and advantageous for use, all as will be hereinafter more fully set 30 forth.

The novel features of the invention will hereinafter be definitely claimed.

In order that my invention may be the better understood, I will now proceed to describe the same with reference to the accompanying drawings, wherein

Figure 1 is a view in elevation of a scaffold constructed in accordance with an embodiment of my invention and in applied 40 position;

Fig. 2 is a detached view in perspective of one of the beams employed in my invention as herein disclosed;

Fig. 3 is a detached view in perspective of 45 one of the legs as herein embodied; and

Fig. 4 is an elevational view disclosing my improved scaffold assembled for use as a horse.

As herein disclosed, my improved scaffold 50 comprises two coacting sections and when applied upon a roof one section serves to coact with the second section for maintaining the scaffold as a whole in proper position. As each of the sections is substantially identical, it is thought that a description 55 of one will suffice for both.

As herein disclosed, each of the sections of my improved scaffold comprises an elongated channel beam 1 of predetermined length and having pivotally engaged with its 60 outer end the upper section 2 of a supporting leg L, said pivotal connection 3 being such as to permit said section 2 being separated from the beam 1 as desired.

Coacting with the section 2 is a second 65 section 4 of predetermined dimensions and provided with an elongated longitudinally disposed slot 5 through which the clamping members 6 carried by the section 2 are disposed. By this arrangement it will be perceived that the sections 2 and 4 may be longitudinally adjusted in order to maintain the beam 1 in a horizontal position irrespective of the inclination of the roof to which the scaffold may be applied. The lower end 70 of the section 4 is enlarged transversely to afford the foot 7 provided with the toothed engaging edge 8 for a purpose which is believed to be self-evident.

The flanges of the beam 1 are downwardly 80 disposed and are provided adjacent their opposite ends with the transversely aligned openings 9 to afford a means whereby the brace member B may be engaged therewith. As herein disclosed, the brace B comprises 85 two sections and when the device is adapted to be employed as a scaffold the upper end of the section 10 of the brace B is pivotally engaged with the inner end of the beam 1 through the medium of the removable pin 11, while the second section 12 of the brace B is pivotally engaged with the leg L. In order that the sections 10 and 12 may be longitudinally adjusted one relative to the other, the brace B is provided with an elongated longitudinally disposed slot 14 through 90 which is adapted to be disposed the clamping members 15 carried by the second section 12.

When in applied position, the inner ends 100 of the beams 1 are adapted to contact with the ridge portion of a roof and are detachably connected one with the other through the medium of the removable pin 16.

I also find it of advantage to provide the 105 beams 1 with the loop rods 17 which serve to assure the scaffold boards being maintained against accidental displacement.

As is illustrated particularly in Fig. 4, the sections of my improved scaffold may be assembled in such a manner as to serve as a horse and in which event the legs L are 110

secured to the opposite ends of a beam 1 and the braces B disposed in crossed relation, as particularly illustrated in said Fig. 4, and it is for this reason that the opposite ends 5 of the flanges of each of the beams 1 are provided with the transversely alined openings 9 hereinbefore referred to. The braces B are of a width less than the width of the beams 1 and are of such relative widths as to 10 permit the same to assume the crossed relation as disclosed in Fig. 4.

From the foregoing description, it is thought to be obvious that a scaffold constructed in accordance with my invention is 15 of an extremely simple and comparatively inexpensive nature and is particularly well adapted for use by reason of the convenience and facility with which it may be assembled, and it will also be obvious that my invention is susceptible of some change and modification without material departure from the principles and spirit thereof and

for this reason I do not wish to be understood as limiting myself to the precise arrangement and formation of the several 25 parts herein shown in carrying out my invention in practice, except as hereinafter claimed.

I claim:

A scaffold structure comprising two 30 beams, a leg at each end of each beam and a brace connecting each leg to its beam, the leg and brace at one end of each beam being detachable, and means for detachably connecting such ends of the two beams together 35 whereby either two platform supports or a single gable spanning support may be provided.

In testimony whereof I hereunto affix my signature in the presence of two witnesses.

FRANK W. WATSON.

Witnesses:
